SNAP-ON TRIM STRUCTURE

Frederick J. Westrope, Pleasant Ridge, Mich., assignor, by mesne assignments, to Reconstruction Finance Corporation, Detroit, Mich., a corporation of the United States

Application October 30, 1940, Serial No. 363,433

4 Claims. (Cl. 189—88)

This invention relates to trim structures for ornamenting furniture, vehicles and the like, and particularly to structures which hold fabric in association therewith.

One object of this invention is to provide a trim structure for furniture or vehicles having means for holding the edges of fabric as well as additional means for ornamenting the junction between the adjacent edges of the fabric.

Another object is to provide a trim structure having fabric holding portions with a projection therebetween, and a separate ornamental trim member snapped into place over the projection so as to cover the projection and assist in holding the fabric against the structure.

Another object is to provide a trim structure having spaced clamping flanges for holding the edge of a fabric and an elongated ridge or rib having a hollow elongated snap-on member superimposed upon the ridge and assisting in holding the fabric in position.

In the drawing:

Figure 1 is a front elevation of a preferred embodiment of the snap-on trim structure of this invention showing the fabric and the snap-on member partly broken away to disclose the remaining structure more clearly.

Figure 2 is a cross section along the line 2—2 in Figure 1.

In the decorating and covering of automobiles and furniture, it is necessary to secure the ends of the fabric firmly in position. At the same time, it is also necessary to cover the line along which the fabric is anchored. In prior structures of this character, however, it has been difficult to conceal this line and at the same time to make it accessible and convenient for manufacturing purposes.

In the present invention, a projecting ridge is provided adjacent the edge line of the fabric. Over this projecting ridge there is snapped a hollow member of approximately U-shaped cross-section, this hollow member serving to conceal the ridge and also the junction line or anchorage line of the fabric. At the same time, moreover, the hollow member may also serve to hold the fabric more securely against the structure and thus increase the strength of the anchorage.

Referring to the drawing in detail, Figures 1 and 2 show a preferred embodiment of the invention as consisting of a fabric-holding member 10 and a snap-on member 11. The anchorage member 10 consists of an elongated structure having spaced rear walls 12 with a hol-

low projecting ridge 13 therebetween and having a restricted neck 14. The rear walls 12 are bent back on themselves around outer edges 15, with the free edge portions 16 directed toward the neck 14 of the ridge 13 and parallel with the rear portions 12. The free edges 17 of the fabric covering 18 are inserted between the portions 12 and 16 and held therebetween, not only by the resilience of the structure but also by indentations (not shown) in the portions 12 or 16.

The ridge 13 is enlarged beyond the neck 14 and is covered by the snap-on member 11 which is sprung into place thereover. The snap-on member 11 is preferably integral with a base portion 19 and edge portions 20.

The edge portions 20 are preferably beaded so that they snap around the enlarged parts 21 of the ridge 13 and spring into place against the neck 14 of the ridge 13. The snap-on member 11 is preferably constructed of plastic material having ornamental characteristics as well as durability and flexibility. The fabric-holding member 10 is conveniently made of metal. In order to serve as ornamentation, however, this metal would require plating if the ridge 13 were left exposed. By the use of the snap-on member 11 of plastic material, however, the metal may be left unplated because it is entirely covered by the snap-on member 11 at its exposed rib 13.

At the same time, the edges 20 of the snap-on member 19 serve to clamp the fabric 18 more firmly against the portions 16, if desired.

In the assembling of the structure, the free edges 17 of the fabric 18 are inserted between the portions 12 and 16 of the fabric holding portion 10 and suitable indentations made, if desired. The snap-on portion 11 is then snapped into position, covering the exposed ridge 13 and also the edge lines 22 where the fabric turns around the edges of the portions 16. In this manner the plastic snap-on member 11 conceals the edge lines 22 and also assists in holding the fabric. Another advantage is that different colors of plastic material may be used for the snap-on members 11, thereby enabling a variety of decoration to be given which is not possible with the use of metallic material alone.

While a specific embodiment of the invention has been described and illustrated, it will be understood that various modifications may be made within the scope of the appended claims without departing from the spirit of the invention.

What I claim is:

1. In a trim structure, an elongated, relatively narrow base member having longitudinally dis-

posed clamping means for securing fabric thereto and an elongated ridge extending therealong, said ridge having an enlarged outer portion and a longitudinally disposed constricted portion between said outer portion and said base member, and a cover member having an enlarged longitudinal recess and inwardly extending edges defining a constricted entrance to said recess, said cover member embracing said ridge and having at least one of its edges extending over the junction of the fabric with said base member.

2. In a trim structure, an elongated, relatively narrow base member having longitudinally disposed clamping means for securing fabric thereto and an elongated ridge extending therealong, said ridge having an enlarged outer portion and a longitudinally disposed constricted portion between said outer portion and said base member, and a cover member having an enlarged longitudinal recess and inwardly extending edges defining a constricted entrance to said recess, said cover member embracing said ridge and having at least one of its edges extending over the junction of the fabric with said base member, the enlarged recess of said cover member extending around and substantially mating with said ridge and the longitudinal edges of said member extending into said constricted portion of said ridge.

3. In a trim structure, an elongated base member with its opposite edge portions bent longitudi-

nally back toward one another and said base member to form a pair of spaced fabric clamping devices, said base member between said edge portions being bent to form a ridge therealong, and an elongated cover member having a recess extending at least partially around said ridge, the edges of said cover member extending over the junction of the fabric with said bent-over clamping edge portions and engaging and urging said fabric and said clamping edges toward and into clamping engagement with said base portion.

4. In a trim structure, an elongated base member with an edge bent longitudinally back upon itself to form a fabric clamping device and a projecting ridge extending longitudinally therealong, said ridge being enlarged at its outer edge and having a constricted portion between said outer edge and said base member, and an elongated cover member having an interiorly enlarged longitudinal recess having inwardly extending edges facing one another to define a restricted entrance to said recess, said edges being engageable with the constricted portion of said ridge, one of said cover member edges extending toward said base portion sufficiently to engage the fabric covering said base member edge and to urge said base member edge into clamping engagement with the edge of the fabric disposed therebetween.

FREDERICK J. WESTROPE.
